UNITED STATES PATENT OFFICE.

RICHARD BUSH, OF BROOKLYN, NEW YORK.

PUMP.

SPECIFICATION forming part of Letters Patent No. 232,935, dated October 5, 1880.

Application filed August 18, 1880. (No model.)

To all whom it may concern:

Be it known that I, RICHARD BUSH, of Brooklyn, in the county of Kings and State of New York, have invented certain new and useful Improvements in Pumps; and I do hereby declare that the following is a full, clear, and exact description of the invention, which will enable others skilled in the art to which it appertains to make and use the same, reference being had to the accompanying drawings, and to letters of reference marked thereon, which form a part of this specification, and in which—

Figure 1 is a side, and Fig. 2 a detail, view 15 of the device.

My invention consists in closing the discharge-pipe by means of a tompon or plug, or its equivalent, and exhausting the air in pipe and pump through opening in tompon or 20 in pipe; also, in the use, at end of induction, of the perforated suction-pipe.

The object of my invention is, first, to provide a means of charging a centrifugal pump without the use of a foot or other valve in 25 pump or pipe; second, to provide a means whereby the choking or overloading of suction-pipe is prevented when pumping coal or other foreign or weighty substances.

In pumping sand, coal, stones, &c., it has 30 always been found difficult to prevent the choking or overloading of the suction-pipe with sand, coal, &c., by reason of a lack of sufficient water to carry the same through pipes and pump. This choking I prevent by 35 the use of holes near the end of suction-pipe,

which admit a supply of water to aid in carrying through the pipe the material entering at the end of said pipe.

In the accompanying drawings, A is the tompon or plug through which, at G, connection is made between interior of discharge-pipe and exhauster B.

D is the discharge-pipe. C is a centrifugal pump. E is the suction-pipe, to which is attached end piece, H, which has bottom end 45 open, and is perforated at F.

In case the bottom opening of the suction-section becomes clogged by coal or other substances the water can pass through the perforations, and the pump will not, therefore, 50 cease operating.

Having thus described my invention, I claim—

1. In combination with a discharge-pipe of a centrifugal pump and the suction-pipe of an 55 air-pump, the plug G, whereby the centrifugal pump can be primed, substantially as described.

2. In combination with a centrifugal pump, the suction-piece having an open bottom and 60 holes in the side, whereby a free flow of water is allowed, and choking by coal or other substances prevented, substantially as described.

Witness my hand this 6th day of August, 1880.

RICHARD BUSH.
